(57) **CLAIM**

The ornamental design for a table stand as shown and described.

DESCRIPTION

FIG. 1 is a top perspective view of a table stand showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top perspective view of the table stand shown in an environment of use with a round tabletop;

FIG. 10 is a top perspective view of the table stand shown in a second environment of use with a rectangular tabletop;

FIG. 11 is an enlarged view of detail 11 in FIG. 1;

FIG. 12 is an enlarged view of detail 12 in FIG. 1; and,

FIG. 13 is an enlarged view of detail 13 in FIG. 3.

The broken lines in the drawings depict portions of the table stand that form no part of the claimed design.

The short-dash-long-dash broken lines are for annotating the enlarged detail views and form no part of the claimed design.
